INVENTOR :
Ernest Vahle,

By Attorneys,

Fraser, Muro & Mauley

UNITED STATES PATENT OFFICE.

ERNEST VAHLE, OF UNION CITY, NEW JERSEY, ASSIGNOR TO A. SCHRADER'S SON, INC., OF BROOKLYN, NEW YORK, A CORPORATION OF NEW YORK.

TIRE-GAUGE INDICATING MEMBER.

Application filed December 8, 1926. Serial No. 153,230.

The present invention relates to improvements in tire pressure gauges of the telescoping indicating sleeve type, and more particularly to the indicating sleeve of such gauges, and aims to provide certain improvements therein.

In the type of pressure gauge described, the pressure indicating sleeve consists of a deep cup closed at its top and open at its bottom, whereat it carries a split spring ring in frictional engagement with the inner wall of the gauge casing. As customarily made, said indicating sleeves are drawn from a sheet metal blank by a succession of cupping operations which gradually deepen the blank to proper form, after which the open end is slightly expanded and provided with an annular groove for accommodating the split spring ring. This process requires repeated annealing operations which adds to its expense and to the time to complete the sleeves.

According to the present invention I provide an indicating sleeve which overcomes the disadvantages hereinbefore set forth, possesses certain distinct advantages thereover and one which can be more quickly and cheaply made. To this end I construct the sleeve from a flat sheet metal blank which is first stamped into suitable shape and then bent to provide a sleeve-like member of prismatic form open and expanded at the bottom, the stamping and bending operations being such that the resulting sleeve will be provided with longitudinal split portions, possessing a degree of resiliency at the bottom thereof, such that when the gauge parts are assembled the frictional engagement between the bottom of the sleeve and the inner wall of the casing will be uniform throughout the range of movement of the sleeve and sufficient to hold said sleeve in any indicating position of the sleeve. The invention also includes other features of novelty which will be hereinafter more fully described.

In the accompanying drawings I have shown certain preferred embodiments of my invention wherein,

Figure 1 is an elevation partly in section of a pressure gauge embodying my invention.

Figs. 2 and 3 are transverse sections taken on the lines 2-2 and 3-3, respectively of Figure 1.

Fig. 4 is a frictional elevation of a slight modification of the invention. 55

Fig. 5 is a section taken on the line 5-5 of Fig. 4.

Fig. 6 is a plan of the sheet metal blank of which the indicating sleeve is formed.

Fig. 7 is a perspective view of the blank 60 in Fig. 6 after being subjected to a preliminary bending operation.

Fig. 8 is a perspective view of the indicating sleeve.

Referring to the drawings let A indicate 65 a pressure gauge of the telescoping indicating sleeve type wherein B is the gauge casing within which is housed an elastic thimble C surrounded by a loading spring D and a telescoping indicating sleeve E. At the foot 70 of the casing B there is provided any conventional form of press-on seat and tire valve depressor herein indicated generally by the reference character F. The foregoing elements constitute a conventional type of 75 tire pressure gauge which differs from the present invention only in the specific form and construction of the telescoping indicating sleeve E.

According to the present invention the indicating sleeve E is preferably of prismatic form for the greater portion of its length and of substantially cylindrical form for the remainder of its length, the top of said member being closed, as at e, and the bottom being open, as shown at e'. The cylindrical portion of the sleeve E is of larger diameter than the prismatic portion, and at the juncture of said portions there is provided a shoulder e². This shoulder is adapted to co-operate with a shoulder b formed at the outer end of the casing B, whereat it is spun inwardly to provide a guide for the longitudinal edges of the indicating sleeve, said shoulders co-operating to limit the outward movement of the indicating sleeve and prevent its removal from the casing. The prismatic structure of the indicating sleeve provides it with a plurality of flat faces upon which the pressure indicia can be conveniently applied, and inasmuch as the longitudinal edges of the prismatic portion are the only portions thereof which engage the casing, it

will be apparent from this construction that the danger of the pressure indicia being 105 eradicated or disfigured due to the sliding

contact of the indicating sleeve with the casing is entirely overcome.

In Figs. 1 and 2 relative rotation between the indicating sleeve and the casing is prevented by slightly indenting the spun-in portion at the outer end of the casing B, as shown at b', but said indentations are not sufficiently great to cause engagement of the flat faces of the prismatic casing therewith, as best shown in Fig. 2. In this embodiment of the invention it will therefore be apparent that in order to read the pressure gauge after having applied it and removed it from a tire valve, it may be necessary to 10 rotate the gauge as a whole in order to obtain the line of coincidence between the pressure indicia line on the indicating sleeve and the top edge of the gauge casing. In the modification shown in Figs. 4 and 5 the 15 indicating sleeve is adapted to be rotated relatively to the casing, as will be apparent from an inspection of Fig. 5. According to this embodiment of the invention, an operator may either turn the entire gauge in order to read an indicated pressure or he may 20 hold the gauge casing in one hand and turn the indicating sleeve until the indicated pressure mark on the sleeve coincides with the top edge of the casing. In this latter 25 operation, however, care must be exercised not to disturb the relative longitudinal relation to which the indicating sleeve has been moved outwardly by the pressure and the 30 top of the gauge casing.

A principal feature of novelty of the present invention resides in the specific construction of the indicating member E, which, as herein disclosed, is formed from a flat sheet metal blank G, as shown in Fig. 6. This blank, which may be formed of sheet brass, iron, steel or other substance, can be stamped out of a sheet in a single operation by a suitable punch or die. The blank consists of a central portion g, preferably of hexagonal form, flanked on both sides by substantially rectangular portions g'. In Fig. 7 the major portions of the parts g' are shown as bent to form troughs which are semi-hexagonal in cross-section, while the outer ends of said portions g' are expanded outwardly to provide portions of semi-circular form in cross-section. If desirable or practicable, the blank shown in Fig. 7 may be formed in a single stamping operation rather than in two distinct operations. The bent portions g' of Fig. 7 are then bent along the lines g² towards each other to provide the split sleeve, as shown in Fig. 8. Owing to the inherent resiliency of the 50 metal, the portions g' when bent toward each other until the edges g³ engage the under faces of the top G, the sleeve will assume the form shown in Fig. 8 with the sleeve walls longitudinally split, as shown at H, 55 and spaced apart a substantial distance at

the open end of the cup, as shown at J. The normal diameter of the open end of the sleeve is substantially greater than the internal diameter of the gauge casing, hence the open end must be somewhat contracted to permit its insertion within the gauge casing. After insertion within the casing, the expanded open end of the sleeve, due to its inherent resiliency and tendency to assume its normal diameter, exerts a force radially outwardly against the inner wall of the casing providing a frictional holding engagement between the sleeve and the casing that is ample to maintain the indicating sleeve in any pressure indicating position to which it is moved. The prismatic portion of the indicating sleeve, however, has only its longitudinal edges in sliding engagement with the gauge casing at the outer spun-in edge b' thereof, hence the frictional holding engagement between the indicating sleeve and the gauge casing is wholly provided between the expanded open end portion of the sleeve and the inner wall of the casing. The inner diameter of the casing being uniform throughout the range of the frictional engagement and movement of the sleeve therewith, it will be apparent that said frictional holding engagement will be uniform for every degree of projection of the sleeve. 95

From the foregoing it will be appreciated that in the present construction of indicating sleeve I have provided a device which can be quickly and cheaply made, one which eliminates the use of a separate spring ring for holding the indicating sleeve in indicating position, and one in which all danger of eradication or marring of the pressure indicia due to repeated sliding engagement with the casing is done away with. Also, that because of the absence of engagement between the pressure indicia and the gauge casing, said indicia may be printed or lithographed upon the flat sheets prior to stamping therefrom the sleeve blanks, and thereby provide an additional saving in the manufacturing cost of such devices. 110

While I have shown and described the preferred embodiments of my invention I desire it to be understood that I am not to be limited to the specific structures disclosed, since various modifications thereof may be resorted to without departing from the spirit of the invention. 115

What I claim is:

1. A pressure gauge comprising a casing and an indicating sleeve telescoping with said casing, said sleeve having a plurality of longitudinally-extending edges providing the sleeve with faces between said edges, the faces of the sleeve being out of sliding engagement with the casing and pressure indicia on the faces of the sleeve. 125

2. A pressure gauge comprising a casing and an indicating sleeve of prismatic form 130

telescoping with said casing, the flat faces of the prism being out of sliding engagement with the casing and pressure indicia on the flat faces of the prism.

- 5 3. A pressure gauge comprising a casing and an indicating sleeve of prismatic form telescoping with said casing, the flat faces of the prism being out of sliding engagement with the casing, and the casing being 10 shaped to co-operate with the longitudinal edges of the prism to prevent relative rotation between the casing and sleeve.

- 15 4. A pressure gauge comprising a casing and an indicating sleeve of prismatic form telescoping with said casing, the longitudinal edges of the prism being in sliding contact with the top of the casing, the faces of the prismatic sleeve being out of engagement with the casing and said sleeve having 20 resilient means frictionally engaging the wall of the casing for holding said sleeve in various indicating positions.

- 25 5. In a pressure gauge, an indicating sleeve formed from what was originally a flat sheet-metal blank which is subsequently

bent into the form of an elongated cup which is closed at its top, open at its bottom, and longitudinally split on its side from top to bottom, said cup being of prismatic form from the closed top to a point 30 near the open bottom and from said point to the open bottom, said cup being expanded to provide resilient walls for frictionally holding the indicating sleeve in indicating positions.

35 6. In a pressure gauge, an indicating sleeve formed from what was originally a flat sheet-metal blank having a portion of polygonal form flanked by substantially rectangular portions, which latter are bent into 40 trough-like form and then subsequently bent along the lines which mark the junction of said portions of the first-named polygonal portion to provide a longitudinally split sleeve of prismatic form having a closed top 45 and an open bottom and which constitutes the indicating sleeve.

In witness whereof, I have hereunto signed my name.

ERNEST VAHLE.
